UNITED STATES PATENT OFFICE.

HILARY N. HOLCOMB, OF EAST BEND, NORTH CAROLINA.

IRONING-TABLE.

No. 866,135.

Specification of Letters Patent.

Patented Sept. 17, 1907.

Application filed November 20, 1905. Serial No. 288,269.

To all whom it may concern:

Be it known that I, HILARY N. HOLCOMB, a citizen of the United States, residing at East Bend, in the county of Yadkin and State of North Carolina, have invented 5 certain new and useful Improvements in Ironing-Tables; and I do declare the following to be a full, clear, and exact description of the invention, such as will enable others skilled in the art to which it appertains to make and use the same.

10 This invention relates to folding ironing tables and one of the principal objects of the same is to provide simple and efficient means for adjusting the height and inclination of the ironing board.

Another object is to provide a folding ironing table 15 which can be quickly folded within a small space when not in use and which can be quickly adjusted in position for use at the required height.

These and other objects are attained by means of the construction illustrated in the accompanying drawings, 20 in which,—

Figure 1 is a perspective view of an ironing table made in accordance with my invention and shown opened out in position for use; Fig. 2 is a similar view of the ironing table adjusted to a lower position; Fig. 3 is a 25 plan view of the adjustable board support; Fig. 4 is a detail view, showing the manner of connecting the pivoted latch to one of the legs and showing the recess in which said latch is to be folded when the board is not in use; Fig. 5 is a plan view of the ironing table in folded 30 condition; and Fig. 6 is an edge view of the same.

Referring to the drawings for a more particular description of my invention, the numeral 1 designates the legs of the ironing table to which are pivotally connected inclined supports 2—2, said supports being pivoted to 35 the legs by the bolts 3—3 and provided with cross braces 4—4. The ironing board 5 is pivoted between the supports 2, as shown. A bifurcated board support 6, comprising two legs 7 pivoted at 8 to the supports 2, is provided at its upper end with a ferrule 9, having a point 40 or spur 10 projecting from the upper end thereof. A latch 11 is pivoted in a recess 12 on the inner side of one of the legs 1, the outer free end of said latch being bent at right angles, as at 14, to engage notches 15 in one of the inclined supports 2. A recess 16 is also formed in the 45 support 2 to accommodate the end of the latch when the parts are in folded condition. Braces 17 connect the two legs 1—1.

From the foregoing it will be obvious that my ironing

table may be adjusted in the position shown in Fig. 1 so that the board will be at a greater height than when adjusted as shown in Fig. 2, thus rendering the board adjustable to the heights of different persons and for different classes of work. It will also be seen that the inclination of the ironing board may be changed at will by the adjustment of the supporting device 6, and that a garment may be quickly placed upon the board or removed therefrom without the upward movement of the free end of the board 5 or the downward movement of the support 6 after the point or spur 10 has been disengaged from the bottom of said board. When not in use the board may be folded within the thickness of the legs 1—1, as shown in Fig. 6.

Various changes in the form, proportion and the minor details of construction may be resorted to without departing from the principle or sacrificing any of the advantages of this invention.

Having thus described my invention, what I claim as new and desire to secure by Letters-Patent is:—

1. An ironing table comprising spaced legs, inclined spaced supports pivotally connected with said legs, one of said supports having spaced notches in its upper face, an ironing board pivotally connected at one end between said inclined spaced supports, and foldable to lie therebetween when closed, a brace rod pivotally mounted on one of said legs and having a hooked end to engage said notches, said brace carrying leg having a longitudinal recess formed in its inner face to receive said brace rod and hold it securely in position when the table is collapsed, and a support for the other end of said ironing board pivotally mounted between said inclined spaced supports and provided with means for engaging said board. 70

2. An ironing table comprising spaced legs, inclined spaced supports pivotally connected at one end with said legs, one of said supports having spaced notches in its upper face, an ironing board pivotally mounted at one end between said inclined spaced supports and foldable to lie therebetween when closed, a brace rod pivotally mounted on one of said legs and having a hooked end to engage said notches and a bracing support for the free end of said board comprising a V-shaped member with its diverging ends pivoted adjacent to the inner faces of the inclined supports respectively and with their free ends converging, and a ferrule arranged on and connecting said converging free ends, said ferrule having a spur projecting from the end thereof to engage the lower face of the free end of the ironing board. 75 85 90 95

In testimony whereof I have hereunto set my hand in presence of two subscribing witnesses.

HILARY N. HOLCOMB.
